UNITED STATES PATENT OFFICE.

JAMES F. ASTLEY, OF PAWTUCKET, RHODE ISLAND.

SHUTTLE-SMASH PREVENTER.

1,180,689.

Specification of Letters Patent. Patented Apr. 25, 1916.

Application filed September 13, 1913. Serial No. 789,692.

To all whom it may concern:

Be it known that I, JAMES F. ASTLEY, a citizen of the United States, residing at Pawtucket, in the county of Providence and State of Rhode Island, have invented a new and useful Shuttle-Smash Preventer, of which the following is a specification.

The present invention relates to shuttle smash preventers, and aims to provide a novel and improved appliance of that character.

The present invention is of value in an automatic weft-replenishing loom, and it is the object of the invention to provide simple yet effective means applicable to a weft-replenishing loom and operable for pressing into place an improperly placed bobbin for preventing a shuttle with an improperly placed bobbin entering the shed from the shuttle box at the magazine end. Thus, if the transerrer of the automatic loom fails to position the bobbin properly in the shuttle at the time of replenishment, the bobbin is moved into place within the shuttle before the shuttle enters the shed by the present device.

The invention is illustrated in the accompanying drawing, wherein:—

Figure 1 is an elevation of the device as applied to the lay and shuttle box of a loom. Fig. 2 is a perspective view of the attachment, portions being broken away.

In the drawing, there is illustrated a lay 1 having upon one end thereof the usual shuttle box 2 for receiving the shuttle S. Mounted above the shuttle box 2 at the magazine end is an automatic weft-replenishing or filling supplying mechanism 3 of ordinary construction, and only illustrated diagrammatically, a bobbin being transferred from the magazine into the shuttle at the time of replenishment in the ordinary manner, and it is the object of the present invention to provide means for pressing the bobbin into the shuttle if the bobbin is not properly placed in the shuttle by the transerrer (not shown).

The present attachment embodies a standard 4 supported in any suitable manner in rear of the lay 1 and having a bracket 5 below the lay to which a lever 6 is fulcrumed between its ends. An eccentric or cam 7

bears upon one arm of said lever and is carried by a shaft 8 which can be operated timely by any suitable mechanism, said shaft 55 being readily connected to the operating mechanism of the loom as will be apparent to those skilled in the art. The other arm of the lever 6 is connected by a vertical link 9 with an L-shaped lever 10 having one arm 60 fulcrumed between its ends to the upper end of the standard 4 adjacent and in rear of the lay and shuttle box. The fulcrum of the lever 10 is indicated at 11, and the other arm of said lever extends across the lay adjacent 65 the mouth of the shuttle box, the lower edge of the arm 12 being cut on a compound curve to coöperate properly with the shuttle and its bobbin. The lever 10 is oscillated properly through the medium of the cam 70 or eccentric 7 which oscillates the lever 6, whereby the arm 12 is moved downwardly to operative position when the shuttle leaves the shuttle box, and the arm 12 is moved upwardly when the shuttle enters the shuttle box. The device is arranged to operate, either by gravity or spring tension, to tend to assume the dotted line position in Fig. 1, when the cam 7 is moved upwardly. The preventer is thus operated to move the arm 80 12 thereof downwardly when the shuttle leaves the shuttle box, and this will prevent the shuttle from entering the shed should the bobbin of the shuttle be improperly placed.

85

What is claimed is:

The combination with the lay of a loom, of a smash preventer embodying an L-shaped member one arm of which forms a lever pivotally mounted adjacent the lay, the other 90 arm of the L-shaped member extending across the lay to move up and down and to press down an improperly placed bobbin into a shuttle passing under said member, and means for oscillating said member to 95 move the second mentioned arm thereof to and from the lay.

In testimony that I claim the foregoing as my own, I have hereto affixed my signature in the presence of two witnesses.

JAMES F. ASTLEY.
